UNITED STATES PATENT OFFICE.

BENJAMIN L. MINK, OF PHILADELPHIA, PENNSYLVANIA.

DESIGN FOR A FLAG.

52,896.

Specification for Design.

Patented Jan. 14, 1919.

Application filed June 13, 1918. Serial No. 239,896. Term of patent 7 years.

To all whom it may concern:

Be it known that I, BENJAMIN L. MINK, a citizen of the United States, residing at Philadelphia, in the county of Philadelphia and State of Pennsylvania, have invented a new, original, and ornamental Design for Flags, of which the following is a specification, reference being had to the accompanying drawing, forming a part thereof.

The figure is a face view of a flag, showing my new design.

I claim:

The ornamental design for a flag as shown.

BENJAMIN L. MINK.
